UNITED STATES PATENT OFFICE.

JESSE E. WILHELM, OF CLEVELAND, OHIO, ASSIGNEE TO THE GREAT LAKES DREDGE & DOCK COMPANY, OF CHICAGO, ILLINOIS, A CORPORATION OF NEW JERSEY.

REINFORCED-CONCRETE PILE AND METHOD OF MAKING THE SAME.

1,225,385.

Specification of Letters Patent.

Patented May 8, 1917.

Application filed November 3, 1915. Serial No. 55,233.

To all whom it may concern:

Be it known that I, JESSE E. WILHELM, a citizen of the United States, residing at Cleveland, in the county of Cuyahoga and State of Ohio, have invented a certain new and useful Improvement in Reinforced-Concrete Piles and Methods of Making the Same, of which the following is a full, clear, and exact description, reference being had to the accompanying drawings.

This invention relates to reinforced piles. One of the objects of the invention is to provide a concrete pile which shall be simple, durable and cheap to manufacture. Another object is to so construct the pile that it may be conveniently provided with devices for interlocking adjacent piles, and a more specific object is to provide for the attachment of these interlocking devices without interfering with the use of the pile without such interlocking means, or without detracting from its strength, and a feature of my construction is that, when the interlocking devices are used they serve to add to the strength of the pile.

Another object of the invention is to provide a simple effective means for anchoring the lower end of the pile to rock against which the pile may be driven. This I accomplish by providing the pile with an axial opening extending from end to end thereof and through which a suitable drill may be operated to prepare the rock at the lower end of the pile for anchoring the pile thereto.

Still another object of my invention is to provide, in connection with a longitudinal passage, a means for conveniently forcing water downwardly through the passage to the point of the pile for purposes of "jetting" to facilitate driving the pile to position.

Another object of the invention is to provide a simple method for constructing such pile providing the most convenient operation of a simple mold in which the pile may be cast and the most convenient assembling of the pile with interlocking members. A mold for making such pile is shown, described and claimed in my application on forms for casting reinforced concrete piles, filed March 30, 1916, Serial No. 87,754.

In carrying out my invention the pile is cast in a mold comprising two or more longitudinal separable sections having transverse inwardly extending ribs or projections

adapted to form transverse grooves around the perimeter of the pile. These grooves are preferably spaced apart and extend substantially half way around the pile, and those extending in one direction are offset 60 or intermediately positioned with relation to those extending in the other direction. These transverse grooves meet oppositely positioned grooves extending preferably throughout the length of the pile and which 65 are formed when the pile is cast. The interlocking members have one edge adapted to coact with an interlocking device on the adjacent pile and have the other edge adapted to seat in the longitudinal grooves and are 70 preferably provided with a series of openings registering with the transverse grooves. Rods lying in these grooves have their ends projecting through the openings in the interlocking members and nuts on the ends of 75 these rods may act to effectively hold the interlocking members in place.

The longitudinal opening along the axis of the pile may be formed by a tubular casting or pipe firmly cast into the pile and 80 forming part of the same, or this opening may be formed by a collapsible core which is withdrawn after the concrete forming the pile is set. In either instance the core or the tubular member is positioned with relation to the pile by suitable ties extending 85 around the core or pipe and secured to various longitudinal rods forming part of the reinforcing structure of the pile. A suitable driving point may be provided at the 90 lower end of the pile as will be hereinafter described.

By the use of this method of construction the pile having the longitudinal grooves and the laterally extending grooves and having 95 the opening along the axis, may be used as an ordinary concrete pile. The grooves and the longitudinal opening along the axis do not materially affect the strength of the pile. The longitudinal metal members for interlocking purposes may be set into the longitudinal grooves and secured in place by the U-shaped bolts or rods extending half way around the pile in the transverse grooves, and by this simple addition the pile already 100 formed is converted into a concrete pile having 105 interlocking members or wings. If it is desired to anchor the pile to a rock or other very hard strata through which the pile cannot be driven, a suitable drill may be oper- 110

ated through the longitudinal opening of the pile. This drill is used to drill several feet into the rock, after which a suitable post or anchoring member may be dropped through this opening to the lower end of the pile, where it may extend into the rock and upwardly into the pile.

It follows then that by my invention I have provided three forms of pile in one, first a pile adapted for the ordinary purposes; second a pile adapted for interlocking purposes; third a pile adapted for anchoring to rock or like substance. It is obvious that all three of these features may be used on the same pile when desired. A fourth feature of my pile, which is a very valuable one and is simple and conveniently provided in connection with the longitudinal axial opening is that I may provide a radial opening near the top of the pile through which water may be led to the axial opening and by plugging this axial opening above the radial opening and forcing water through the radial opening the material through which the pile is to be driven may be loosened and caused to flow away from the end of the pile, greatly facilitating driving the same. This is a very desirable feature when driving through quicksand or like material.

My invention is hereinafter more fully described in connection with the accompanying drawings and the essential characteristics are set forth in the claims.

Referring to the drawings, Figure 1 is a side elevation of two of the piles showing the interlocking and anchoring features; Fig. 2 is a plan view of one of the piles showing the interlocking members secured in position; Fig. 3 is a horizontal section through one of the piles before attaching the interlocking devices, showing a portion of the reinforcing means and the means for holding the tubular casing in position while the pile is being cast; Fig. 4 is a transverse section through a mold showing the reinforcing structure and axial tube in position ready for casting a pile; Fig. 5 is a longitudinal sectional detail of the mold shown in Fig. 4, taken on a smaller scale; Fig. 6 is a vertical axial section through the lower end of one form of pile showing the interlocking members and the construction of the cap point and the arrangement of the adjacent portion of the reinforcing structure; Fig. 7 is a transverse section similar to Fig. 3, showing a form of my pile with the central opening formed without the axial tube; Fig. 8 is a sectional view corresponding to Fig. 6, showing an alternative arrangement of the cap and reinforcing structure at the lower end of the pile; Fig. 9 is a somewhat diagrammatic view showing the method of forming the axial opening through the pile by means of a collapsible core; Fig. 10 is an end elevation of such core; Fig. 11 is a detail

of one of the members for securing the interlocking devices in position; Fig. 12 is a detail in the form of a perspective view of a portion of the lower end of the reinforcing skeleton adapted for use with the form of pile point shown in Fig. 8; Fig. 13 is a longitudinal sectional detail showing the members for forming the longitudinal and transverse grooves of the pile, being a section of the mold taken along the joint of the same. The relative scales on which the views above described are drawn is as follows: Figs. 1, 5, 9 and 12 are drawn to the same scale; Figs. 2, 3, 4, 6, 7, 8 and 11 are drawn to a scale substantially twice the scale used for Fig. 1; Figs. 10 and 13 are drawn to larger scales having no definite relation to the other figures.

Referring to the drawings by reference numerals, the concrete pile 1 is preferably of an octagonal form made conical-shaped at its lower end, as indicated at 2, and provided with a metal cap 3 secured to the concrete and adapted to prevent the crushing of the point of the pile while it is being driven.

The method of anchoring the lower end to rock against which it is driven and the means by which I accomplish it is as follows:

The octagonal pile is provided with a longitudinal opening or well extending along its axis from end to end, as indicated at 5. At the lower end the cap member 3 is provided with a suitable opening registering with the axial opening of the pile, normally closed by an inverted cone-shaped cap 7 of concrete or like material which may be readily crushed or drilled out by a drilling member extended downwardly through the opening 5. When the pile is driven down to rock or like material, through which it cannot be driven, a suitable drill is extended downwardly through the opening 5 and operated to drill out the concrete point 7 and drill downwardly into the rock a suitable distance, forming an opening registering with the axial opening 5. The drill is then withdrawn and a post or pin such as indicated at 8 is dropped through the opening 5 to the rock at the lower end. This post when it reaches the lower end preferably extends half of its length into the rock and the other half upwardly into the pile. This post may be made of any suitable material, for example, discarded car axles, make splendid anchoring devices for this purpose. When the anchoring post is in position the opening 5 may be filled with concrete if desired, thereby securely holding the post in position at the lower end and forming a solid pile.

The longitudinal passage may be formed by casting the concrete pile around a tubular pipe-like member 10, (Figs. 3, 4 and 6). This tubular member is suitably held in position in the mold while the pile is cast, as will be hereinafter described. When such

tubular member is used the cap 3 at the lower end of the pile is preferably provided with a bore 12 adapted to fit the exterior of the lower end of the tube, while a shoulder 13 formed integral with the cap member abuts the lower end of the tubular casing. Just below this shoulder 13 which is in the form of an inwardly projecting rib is provided a conoidal recess 14 adapted to receive the concrete point 7, which is preferably cast in position before casting the pile.

While the tube member 10 forms a very smooth and efficient axial opening for the pile and is convenient to use in building the pile, it is obvious that the expense of such tubes may be an undesirable feature. Accordingly I may if desired cast the pile around a collapsible core which is removed when the pile is hardened. Such core is shown in Figs. 9 and 10 as comprising three members 15, 16 and 17 adapted to extend throughout the length of the pile and adapted to nest together, as indicated in Fig. 10, to form a substantially cylindrical core. It will be noted that each of the members comprising the core has a peripheral area of less than half the circumference of the core and the member 15 has two surfaces 18 and 19 which taper toward the center as they approach one end of the pile. Each of the members is shown as provided with an eye 20 by which it may be withdrawn when the pile is set. In operation this core is nested in its proper form with the lower end positioned against the cap point 7, (previously cast in the cap 3) and the pile body is then cast about the core within a suitable mold, as will be hereinafter described. The member 16 is then withdrawn longitudinally, upwardly as shown in Fig. 9, and upon the first upward movement it is at once apparent that this member will become loosened and thereby withdraw freely. The member 16 may be then withdrawn and the member 17 being then entirely free, may follow. This provides the desired longitudinal passage through the pile, and as the core may be used repeatedly the expense of providing this passage is materially reduced. The upper diameter of this core when assembled is preferably slightly larger than the lower end, as shown in the drawings.

The interior of my concrete pile is preferably reinforced by steel structure similar to the usual construction. As shown this reinforcing structure comprises a plurality of spaced-apart longitudinal rods 22 preferably extending substantially throughout the length of the pile. As shown there are eight of these rods positioned on radial lines extending through corners of the octagonal exterior of the pile. The rods are relatively positioned and spaced with relation to each other by encircling rods 23, which are shown

as looping around each of the vertical rods 22. These encircling rods 23 may be provided in any desired number and positioned at separated points throughout the length of the pile. At the lower end of the pile the rods 22 are bent inwardly and then downwardly, as shown in Fig. 6 at 24, where they may rest on or engage a shoulder 25 formed in the cap 3. At 26 (Figs. 6 and 12) is shown an additional encircling rod extending around the inwardly extending portions of the rods. Any desired number of such encircling rods may be provided to suitably reinforce the pile. In Fig. 6 is indicated a means for preventing the cap 3 from becoming inadvertently removed from the lower end of the pile. It comprises an inwardly extending rib 27 formed on an upwardly extending portion of the cap 3 and adapted to firmly engage the concrete when the pile is cast.

In Figs. 8 and 12 I have shown another arrangement of the reinforcing rods and the manner by which they may coöperate with the cap 3 to securely hold the cap in position and additionally strengthen the lower end of the pile. In this form the rods 22 are shown as bent inwardly and downwardly at 24, as described in connection with Fig. 6, and at their lower ends they are bent sharply outwardly at 30. These outwardly extending portions 30 engage beneath an inwardly extending rib 32 forming a shoulder 33 providing the sides of a groove which the outwardly extending projections 30 engage. This method of bracing the lower end of the pile is well adapted for piles having a central opening 5 which is formed with the mold, and in such an instance the projections 30 are held in engagement with the shoulders of the cap 3 by a ring 34 shown as engaging the lower ends of each of the rods, the ring having its opening registering with the longitudinal passage 5 through the pile.

The interlocking feature of the pile will now be described. In casting the pile the concrete is formed with diagonally opposite grooves 36, shown as formed at corners of the octagonal surface and extending throughout the length of the pile. Grooves 36 extend transversely around the outside of the pile from one groove 36 to the other, and the grooves 36 are suitably spaced apart and extend in alternately opposite directions about the pile. Opposite the points where the ends of the grooves 36 meet the grooves 36 are provided with recesses 39 as shown in Figs. 2 and 3. These grooves do not materially affect the strength of the pile nor interfere with its use as an ordinary pile or with the rock anchoring feature heretofore described. The purpose of these grooves, however, is to secure to the pile laterally extending metal wings by 130

which one pile may be interlocked with and braced by the next adjacent pile to form a substantially water-tight wall having great durability and strength.

5 At 40 are indicated interlocking members having portions adapted to fit the grooves 36 and having recesses 41 and tongues 42 adapted to fit in the corresponding recesses of the next adjacent member after the manner of the usual form of interlocking steel sheeting. The members 41 are provided with a series of openings and when in position in the grooves 38, the openings receive the threaded ends of securing rods 44. 10 The ends of these securing members are adapted to receive nuts 45 which occupy the recesses 39 and when tightened clamp the interlocking members securely in position. It will be seen that with a series of these members 44 extending in opposite directions about the pile and each extending through the interlocking members 40 and secured thereto by nuts 45, that the interlocking members are securely held in position. As 15 the members 44 are preferably round rods bent to fit the grooves 38 and lie entirely within the same, these rods do not interfere with the driving of the pile. These members 44 not only securely hold the interlocking members against longitudinal or lateral displacement but they materially add to the strength of the pile. When these interlocking members are secured to the pile a series of piles may be driven side by side with the interlocking members in engagement. The 20 permanency of the concrete piles provides a very strong and rigid wall, through which water is prevented from passing by the interlocking means which serve the further purpose of greatly adding to the strength of such wall.

As shown in Figs. 1 and 6, the inner edges of the interlocking members 40 substantially meet the upper portion of the metal cap 3 at the lower end of the pile, thereby leaving the smallest possible space between this cap and the interlocking members, which preferably extend downwardly to a point substantially level with the lower end of this cap. Thus the possibility of soft earth or water flowing between the piles at their lower ends is reduced to a minimum.

In casting my pile I prefer to use an octagonal mold divided at diametrically opposite points and thereby comprising two half-mold members 50 and 51 adapted to be secured together by suitable angles 52 as indicated in Fig. 4. At one end of this mold 25 may be provided any suitable means (not shown) for holding the cap 3 in position during the casting of the pile. Such means preferably cooperate with a groove indicated at 54, on the exterior of the cap, 30 which, as heretofore stated, is previously

provided with the point 7 cast in position. The grooves 38 are formed by inwardly extending ribs 56, carried by the mold and shown as provided with enlarged portions 58 at their opposite ends adapted to stand against and position inwardly projecting longitudinal ribs 60 which form the longitudinal grooves 36 in the pile. The detail in Fig. 13 indicates the shape of the ribs 56 which extend through notches in the longitudinal ribs 60, while the enlarged ends 58 of the ribs 56 stand alternately at opposite sides of the ribs 60, thereby positioning the same and serving to form the cavities 39 for the nuts on the rods 44, as described. 35

The section in Fig. 4 indicates the reinforcing structure in position in the mold. The casing 10 is shown as held in position by tie rods 62 which preferably loop at their ends around diametrically opposite rods 22. One of these tie rods 62 may extend around one side of the tube 10 or the collapsible core for the central opening, and then several feet along the mold or tube another tie member may extend around the 40 opposite side of the mold or tube and be attached to the same vertical rods 22. Still farther along others of these tie members similarly arranged, may extend from others of the vertical rods 22, thereby leaving as 45 much open space as possible to permit the free flowing of concrete into the mold.

The reinforcing skeleton may be positioned in the mold in any suitable manner. As a convenient means I have shown loops 104 64, which may be formed at the ends of tie rods 62, projecting outwardly past the rods 22, engaged thereby, and adapted to extend into and engage corners of the mold as shown. Thus the reinforcing skeleton and 108 collapsible core or tube 10 is centrally positioned while the concrete is poured into the mold.

The means provided for jetting my pile comprises a radial passage 66 (Figs. 2 and 11) 9) extending from the exterior of the pile to the longitudinal opening 5. When it is desired to jet the pile it is only necessary to make an opening through, or destroy the point 7, plug the longitudinal passage at 115 the upper end of the pile above the radial passage 66, connect suitable pipe line to the passage 66, and force water therethrough. The passage 66 may be formed in any suitable manner, as by positioning a short piece 120 of pipe in the mold while the pile is cast.

From the foregoing description it will be seen that I have provided a strong and simple pile which may be used in the many ways described, and I have provided a simple and inexpensive method of manufacturing such piles.

Having thus described my invention what I claim is:

1. The combination of a pile; longitudi-

5 nally extending interlocking wings projecting laterally from the sides of the pile, a series of securing rods extending perimetrically about the outer surface of the pile and spaced apart, and means carried by each of said rods for convenient attachment of each of the rods to the longitudinally extending members, whereby these members are securely mounted on the pile.

10 2. The combination with a pile, of an interlocking member extending longitudinally along the same, transverse grooves extending around the outside of the pile, and securing members lying in said grooves and adapted to be attached to the interlocking member whereby it may be held in position on the pile.

15 3. The combination of a pile, longitudinal grooves formed in the surface of the pile, transverse grooves extending around the outside of the pile between the longitudinal grooves, interlocking members adapted to seat in the longitudinal grooves, securing members adapted to lie in the transverse grooves, and means for clamping the last named members to the interlocking members.

20 4. The combination of a concrete pile having longitudinally extending grooves in its surface, a series of spaced-apart transverse grooves extending around the outside of the pile from one longitudinal groove to another, interlocking members adapted to seat in the longitudinal grooves, rods lying in the transverse grooves and extending through the interlocking members, and nuts adapted to be threaded on the ends of said rods to secure the interlocking members in position.

25 5. The combination with a concrete pile having a point at one end, of longitudinal grooves extending throughout the length of the pile and having their bottoms terminating on the sloping surface of the point, a metal cap on the point secured to the pile having its upper edge terminating adjacent the lower end of said groove, interlocking members adapted to engage said grooves, and means for securing them in position.

30 6. The combination with a pile body, of interlocking metal wing members having a portion adapted to fit and be secured to the sides of the pile body, the remaining portion adapted to extend laterally therefrom and provided at its outer edge with interlocking members for coöperating with similar devices on an adjacent pile, and a series of members encircling the pile body around the exterior thereof and secured to the interlocking members.

35 7. The combination with a pile body formed of artificial material, interlocking members, surfaces at the exterior of the pile body forming a seat for the inner edge of the interlocking members positioned after

the pile body is formed, a tapered portion at one end of the pile, a metal cap forming a part of said tapered portion, said interlocking members extending along the pile and opposite the tapered portion substantially meeting and extending past said cap and terminating substantially even with the lower end thereof.

40 8. The combination with a concrete body having a plurality of longitudinal grooves in its surface, a metal interlocking member seating in each of said grooves and having its outer edge adapted to coöperate with similar members on adjacent piles, a plurality of transverse grooves in the surface of the pile extending around the same and meeting the longitudinal grooves, and securing members seating in said transverse grooves lying substantially entirely within the same and having their ends extending through and secured to the interlocking members.

45 9. A concrete pile body having in its exterior surface a longitudinal groove and grooves extending transversely around the pile from the longitudinal groove, said grooves being adapted to receive interlocking and securing members respectively.

50 10. A concrete pile body cast with a longitudinally extending groove and a series of perimetric grooves communicating with the longitudinal groove, said grooves being adapted to receive interlocking and securing members respectively.

55 11. A concrete pile body cast in a mold and formed with a plurality of longitudinally extending grooves in its exterior surface and transversely extending grooves on the exterior leading from one of the longitudinal grooves to another being longitudinally offset with relation to each other.

60 12. The method of making a concrete pile consisting of casting the pile in a mold and forming on the exterior surface perimetric grooves, then securing a laterally extending wing to the pile by transverse members lying in said grooves.

65 13. The method of making a concrete pile consisting of casting the pile with a longitudinal groove in the exterior thereof, then placing a laterally projecting interlocking wing in said groove and securing the same in place by a series of transverse members around the exterior of the pile.

70 14. The method of making a concrete pile consisting of casting the pile in a mold and at the same time forming a longitudinal groove in the exterior, then placing one edge of a laterally extending wing in said groove and securing the same in position by members extending transversely around the pile.

75 15. The method of making an interlocking concrete pile consisting of casting the body of a pile in a mold and forming in its exterior a longitudinally extending

- groove and transversely extending grooves communicating with the longitudinal groove and securing interlocking members in the longitudinal groove by members placed in 5 the transverse grooves.
16. The method of manufacturing an interlocking concrete pile consisting of casting the pile in a mold and at the same time forming in the exterior thereof longitudinal 10 grooves and transversely extending grooves communicating at each end with the longitudinal grooves, then placing in each of said longitudinal grooves one edge of an interlocking member, and then placing rods 15 in said transverse grooves and securing the ends of said rods to the interlocking members.
17. The method of making an interlocking concrete pile consisting of casting the 20 pile in a mold and forming in its periphery a longitudinal groove and transverse grooves extending around the exterior of the pile and communicating with the longitudinal grooves at longitudinally separated 25 points and forming cavities at the sides of the longitudinal grooves opposite the ends of the transverse grooves, placing one edge of an interlocking member in said longitudinal groove, placing rods in said transverse 30 grooves extending through the longitudinal members, and then securing them thereto by means occupying said recesses.
18. The method of making an interlocking concrete pile consisting of casting the 35 pile in a mold and forming in its exterior longitudinally extending grooves and transverse grooves communicating with the longitudinal grooves, said transverse grooves extending laterally in opposite directions 40 about the pile and being longitudinally offset, and at the same time forming cavities at the sides of the longitudinal grooves and opposite the ends of the transverse grooves, and then placing in said longitudinal grooves 45 interlocking members, placing rods in said transverse grooves and extending their ends through the interlocking members, and then securing the interlocking members in position by nuts on the ends of the rods and 50 occupying said cavities.
19. A method of making reinforced concrete piles comprising casting the pile in a mold about a reinforcing skeleton, at the same time forming in the outer surface thereof longitudinal grooves extending substantially throughout the length of the pile, and then placing interlocking members in said longitudinal grooves and securing the same in position by members lying around the exterior of the pile. 55
20. The process of making reinforced concrete piles comprising casting the pile in a mold in which a reinforcing skeleton is suitably positioned, at the same time forming longitudinal grooves in the outer surface of the pile extending throughout the length of the same, forming transverse grooves extending around the exterior of the pile from one longitudinal groove to another, the transverse grooves extending in 60 one direction being offset relative to those extending in the opposite direction, during the casting forming recesses in the surface of the pile opposite the points where the transverse grooves meet the longitudinal 65 grooves, then seating a portion of interlocking metal members in the longitudinal grooves and securing the metal members in position by rods extending through the same and lying in said transverse grooves 70 and then applying nuts occupying said recesses and clamping the interlocking members in position. 75
21. A method of manufacturing a reinforced concrete pile adapted to be anchored to rock consisting of casting the pile in a mold about a core providing an axial passage and while the concrete is soft forming in the exterior a longitudinal groove, placing a portion of a laterally projecting interlocking member in said groove and securing said member in position by means extending around the exterior of the pile, and during the casting securing at the lower 80 end of the pile a suitable cap point having an opening registering with the longitudinal 85 passage.
- In testimony whereof, I hereunto affix my signature.
- JESSE E. WILHELM.
